INVENTOR

William Arthur,
BY George E. Gengelback
ATTORNEY

UNITED STATES PATENT OFFICE.

WILLIAM ARTHUR, OF NEWARK, NEW JERSEY, ASSIGNOR TO THE NEWARK WATCH-CASE MATERIAL COMPANY, OF SAME PLACE.

DESIGN FOR A CUFF OR SLEEVE BUTTON.

SPECIFICATION forming part of Design No. 32,272, dated February 27, 1900.

Application filed January 20, 1900. Serial No. 2,212. Term of patent 31 years.

To all whom it may concern:

Be it known that I, WILLIAM ARTHUR, a citizen of the United States, residing at Newark, in the county of Essex and State of New Jersey, have invented and produced a new and original Design for Cuff or Sleeve Buttons, of which the following is a specification, reference being had to the accompanying drawing, forming a part thereof, and which shows 5 in side elevation a cuff or sleeve button, and more particularly that style or kind thereof generally known and referred to as a "link-button."

As shown in the drawing, the leading or 10 material feature of my design consists of two

knobs or buttons proper, A, connected by a bar or link B, each of said buttons or knobs having a series of ribs C and corrugations D encircling or extending around it, the center E being left plain.

Having described my invention, what I claim as new, and desire to secure by Letters Patent, is—

The design for a cuff or sleeve button as herein shown and described.

WILLIAM ARTHUR.
